ERIC BROWN, OF BADEN, SWITZERLAND.

MULTICYLINDER TWO-STROKE-CYCLE INTERNAL-COMBUSTION ENGINE

Application filed April 15, 1926, Serial No. 102,278, and in Germany May 11, 1925.

This invention relates to multi-cylinder two-stroke cycle internal combustion engines having exhaust ports distributed substantially uniformly around the periphery of each cylinder, and which are superposed above scavenging air ports that are likewise distributed substantially uniformly around the periphery of each cylinder, these two rows of ports being uncovered successively by the piston towards the end of its working stroke and covered in the opposite order.

The general object of the invention is the provision of means for the purpose of enabling the exhaust and supervening scavenging operations in each cylinder to take place truly concentrically with the cylinder axis.

Another object of the invention is to free the cylinder liner of heat stresses resulting from the difference in temperature between the adjacent belts of hot exhaust gases and cold scavenging air surrounding the liner.

Other and further objects of the invention will be pointed out or indicated hereinafter or will be apparent to one skilled in the art upon an understanding of the invention or its employment in practice.

In the accompanying drawings forming part of this specification I illustrate in diagrammatic fashion various arrangements in which the invention may be embodied, but it is to be understood that the invention as defined in the claims is not to be construed as limited to any of these illustrative forms.

In the drawings:—

Figure 1 is a section along 1—2 of Figure 2;

Figure 2 a section along 3—4 of Figure 1, and

Figure 3 a section along 5—6 of Figure 1 of an application of the invention to a single acting engine;

Figure 4 is a section along 16—17 of Figures 5 and 6;

Figure 5 a half section along 18—19 of Figure 4, and

Figure 6 a half section along 20—21 of Figure 4 of an application of the invention to a double acting three cylinder engine;

Figures 7 and 8 show in section particular forms of port on an enlarged scale.

Two-stroke cycle internal combustion en-

gines of the type referred to have many advantages, among which are:—

1. A maximum cross sectional area of port becomes available immediately the ports are uncovered owing to the utilization of the whole periphery of the cylinder bore.

2. The formation and maintenance of eddying bodies of inert gas during the scavenging operation is avoided.

3. The path of the scavenging air is shortened.

4. The part of the stroke during which the ports are operated is reduced to a minimum; and

5. The heat stresses and expansions due to heating of the cylinder, piston and piston rod as far as these are affected by the flow of exhaust gases and scavenging air are perfectly symmetrical with the cylinder axis.

In order to obtain these advantages to the full extent it is necessary that the exhaust and scavenging operations shall take place truly concentrically with the cylinder axis, as otherwise there will be one-sided exhaust and scavenging currents which defeat the object aimed at. It is a condition, therefore, that the pressure behind each exhaust port and the pressure in front of each air scavenging port shall each remain approximately completely balanced during the operations in question.

The object of the present invention is to provide means for fulfilling these conditions, that is to effect these pressure equalizations in a technically perfect manner in multi-cylinder two-stroke internal combustion engines of the port exhausting and scavenging type referred to.

According to this invention these means consist in connecting the exhaust ports to two exhaust passages or manifolds, that are located one on either side of the row of cylinders with respect to a plane passing through the shaft and cylinder axes, and that the scavenging air ports are fed from two air supply passages, that are likewise located one on either side of the row of cylinders with respect to a plane passing through the shaft and cylinder axes.

In this way technically detrimental differences in pressure behind the exhaust ports and in front of the scavenging air ports are prevented, as the exhaust gases or scav-

enging air do not flow around one side of the cylinder only, as in the case in this type of engines exhausting and scavenging through ports as hitherto constructed. The invention is particularly useful in cases where the cylinders are placed close together.

7 are exhaust ports distributed over the entire periphery of the cylinder bore and 10 uncovered by the piston at the end of the power stroke and 8 are scavenging ports also distributed around the entire periphery. The exhaust passage is divided into two halves 9 and 10 which are placed at either 15 side of the engine symmetrically to the plane 11-12 passing through the shaft and cylinder axes. By this means in spite of the distance between the cylinders namely 13° of Fig. 2 plus 13° of Fig. 3 being small the 20 pressure is equalized behind the outlets of the exhaust ports sufficiently for obtaining true axially concentric scavenging. For correct functioning it is essential that the extensions 25 of the exhaust passages 9 and 10 as far as their junction with one another or as far as where they pass to the outside shall each offer the same resistance to the flow. Similarly the scavenging air passage is divided into two parts 14 and 15, whereby the air 30 pressure in front scavenging ports 8 leading from the passages 14 and 15, in which there is the same pressure, is equalized as far as is required to ensure true axially concentric scavenging.

35 In Figures 4, 5 and 6 a row of double acting cylinders are shown, each cylinder half of which exhausts into a pair of exhaust manifolds 22, 23 and 24, 25 respectively, which manifolds are so arranged that a zone 40 26 is formed on either side of the plane 20-21 whereby a perfectly unobstructed wide space is produced, which is laterally bounded by the walls 27, 28, 29, 30 and to which air is supplied through pipes 31, 32 by the scavenging air pump. In the example shown the exhaust passages are made 45 in the form of boxes into which the cylinders or their liners 33, 34 extend and are fixed by means of their flanges 35, 36.

50 In order to allow for the relative axial expansion of and relief of heat stresses in the cylinder liners, due to the proximity of the belts of hot exhaust gases and cold scavenging air around these entire peripheries, 55 they are in the example divided into three sections 33, 37, 34, whereby the inner ends of the two outer sections 33 and 34 are crenelated and the teeth so formed are adapted to slide axially and substantially 60 gas tight in the gaps between teeth formed by crenelations at either end of the middle section 37, so that, when the teeth are in engagement the gaps in the outer sections 65 form the exhaust ports 38, 39 and the gaps in the middle section the scavenging ports

40, 41 around the entire periphery of the cylinder thus forming by their engagement both the exhaust and the scavenging air ports.

The middle section 37 of the cylinder 70 linings may act as centering and distancing members between the exhaust boxes 22-23 and 24-25. For this purpose they are provided with projecting parts 46, with axial abutment surfaces 47-48 and with cylindrical centering surfaces 49-50. The whole is held together and fixed to the frame of the engine by means of bolts 51 extending right through the different parts.

The ends of the exhaust ports 52-53, 80 where they open into the collecting exhaust passages 22-23 may be formed like deflecting blades, so as to prevent the formation of eddies and to assist the flow of the exhaust on either side by suction. 85

In the case of internal combustion engines of large dimensions the collecting exhaust passages 22-23 may be bolted on laterally.

Preferably the middle section 37 of the 90 cylinder lining is cooled by scavenging air only. The teeth 54 between the exhaust ports if at all are preferably cooled by means of tubes 55 extending into them, through which the water for the cooling 95 jacket flows in or out. For this purpose annular ducts 56, 57 and connecting branches 58, 59 are provided at the cylinder ends. The cooling water is preferably distributed to the tubes 55 by baffles. 100

What I claim is:—

1. A two-stroke cycle internal combustion engine having in combination a plurality of cylinders, exhaust ports substantially uniformly distributed around the periphery of each of said cylinders, scavenging air ports uniformly distributed around the periphery of each of said cylinders, working pistons uncovering said exhaust and scavenging air ports and covering same in opposite order, a plane substantially common to the axes of said cylinders, two exhaust passages common to said cylinders and arranged one on each side of said plane, communication passages between the exhaust ports of each of said cylinders and each of said exhaust passages, two scavenging air passages common to said cylinders and arranged one on each side of said plane, and communication passages between said scavenging air ports of each of said cylinders and each of said scavenging air passages. 115

2. A two-stroke cycle internal combustion engine having in combination a plurality of double acting cylinders, exhaust ports substantially uniformly distributed around the periphery of each working end of each of said cylinders, scavenging air ports substantially uniformly distributed around the periphery of each working end of each of said 125 130

cylinders, a double acting piston in each of said cylinders uncovering said exhaust and scavenging air ports and covering same in opposite order, a plane substantially common to the axes of said cylinders, four exhaust passages pairwise in common to each working end of said cylinders, and arranged so that one pair is situated on each side of said plane, communication passages between 5 said exhaust ports and said exhaust passages, two scavenging air passages arranged one on each side of said plane and common to the working ends of said cylinders, and a communication passage between said scavenging air ports and said scavenging air passages.

3. A two-stroke cycle internal combustion engine having in combination a plurality of double acting cylinders, each cylinder divided into three aligned portions, each said portion interengaging in axial slidable crenellations of the abutting portion, axial gaps between tips of the interengaging teeth of the centre portion and the roots of the teeth 20 of said external portions of said cylinder forming exhaust ports substantially uni-

formly distributed around the periphery of each working end of each of said cylinders, axial gaps between the roots of the interengaging teeth of the centre portion and the 30 tips of the teeth of said external portions of said cylinder forming scavenging air ports substantially uniformly distributed around the periphery of each working end of each of said cylinders, a double acting piston in 35 each of said cylinders uncovering said exhaust and scavenging air ports and covering same in opposite order, a plane substantially common to the axes of said cylinders, four exhaust passages pairwise common to each 40 working end of said cylinders, one pair on each side of said plane, communication passages between said exhaust ports and said exhaust passages, two scavenging air passages of which one is on each side of said 45 plane and common to the working ends of said cylinders, and a communication passage between said scavenging air ports and said scavenging air passages.

In testimony whereof I have signed my 50 name to this specification.

ERIC BROWN.
